[57] CLAIM

The ornamental design for automotive safety strobe light, as
shown and described.

DESCRIPTION

FIG. 1 is a perspective view of automotive safety strobe light
showing my new design, with the wires broken away to
indicate indeterminate length;

FIG. 2 is a front view thereof, with the wires omitted for
convenience of illustration only;

FIG. 3 is a rear view thereof;

FIG. 4 is a right side view thereof;

FIG. 5 is a top view thereof; and,

FIG. 6 is a bottom view thereof.

The left side view is a mirror image of FIG. 4.
